NUMBER-SETTING MECHANISM FOR A CALCULATING AND SUCH MACHINES

BACKGROUND OF THE INVENTION

1. Field of the Invention

The present invention relates to a number-setting mechanism for a calculating or like machine in which decimal numbers are entered, comprising a store with a plurality of decimal orders having in each order at least one member adapted to be set in a plurality of different positions.

2. Description of the Prior Art

Various setting mechanisms of this type are known. In one of these mechanisms, the numbers set or entered on a keyboard selectively position code bars, the positions of which are transferred through the medium of a decoder to a wheel-type setting store. This mechanism has a large number of parts, as a result of which it becomes very complicated and costly.

SUMMARY OF THE INVENTION

The technical problem which the present invention is intended to solve is to produce a mechanism for setting a series of storage members for decimal numbers, coded for example through the medium of a numerical 10-key keyboard, without any intermediate coding device for the decimal numbers that are entered.

According to the invention there is provided a number setting mechanism for a calculating machine or other machine in which decimal numbers are entered, comprising a mechanical setting store with a plurality of decimal orders having in each order at least one settable member adapted to be set in at least two different positions, a pair of complementary stepped profiles adapted to be shifted variably according to the position which the settable member is to reach and adapted to be read simultaneously by a pair of reading elements movable for complementary strokes, two positioning members being arranged to shift in opposite directions under the control of the reading elements respectively and being adapted to engage the settable member from opposite directions to bring it positively from any previously occupied position to the said position to be reached.

In a preferred embodiment of the invention, the stepped profiles are positioned on the depression of each key of a compact keyboard through the medium of a pair of encoding devices which are rendered operative automatically and alternately on the depression of the successive keys in such a manner as to permit the depression of a new key even during the setting of the number corresponding to the preceding key.

The mechanism can be provided with two setting stores adapted to be set by two pairs of positioning members, a common actuating device being adapted to actuate the said pairs of positioning members alternately and to be changed over for the actuation on the depression of each of a series of function keys.

BRIEF DESCRIPTION OF THE DRAWINGS

Two preferred embodiments, given by way of example, are dealt with in the following description and shown in the accompanying drawings, in which:

FIG. 1 is a partial side view from the left of a first embodiment of the invention;

FIG. 2 is a partial section on the line II-II of FIG. 1;

FIG. 3 is a partial section on the line III-III of FIG. 2;

FIG. 4 is a front view, partly in section, of the mechanism of FIG. 1;

FIG. 5 is a partial section on the line V-V of FIG. 2;

FIG. 6 is a partial plan view of the mechanism of FIG. 1;

FIG. 7 is another partial plan view of the mechanism;

FIG. 8 is another partial plan view of the mechanism;

FIG. 9 is a composite diagram of FIGS. 2, 6, 7 and 8;

FIG. 10 is a partial side view of the mechanism of FIG. 1 from the left;

FIG. 11 is another partial side view of the mechanism of FIG. 1 from the left;

FIG. 12 is a composite diagram of FIGS. 1, 10 and 11;

FIG. 13 is a section on the line XIII-XIII of FIG. 7;

FIG. 14 is a section on the line XIV-XIV of FIG. 8;

FIG. 15 is a composite diagram of FIGS. 3, 13 and 14;

FIG. 16 is a diagram of the working cycle of the mechanism embodying the invention shown in FIG. 1;

FIG. 17 is a side view from the left, partly in section, of a second embodiment of the invention;

FIG. 18 is a section on the line XVIII-XVIII of FIG. 17;

FIG. 19 is a partial section on the line XIX-XIX of FIG. 17;

FIG. 20 is a partial section on the line XX-XX of FIG. 18;

FIG. 21 is a diagram of the working cycle of the mechanism of FIG. 17.

DESCRIPTION OF THE PREFERRED EMBODIMENT

General Description

20 A first setting mechanism embodying the invention is incorporated in a calculating machine comprising a numerical 10-key keyboard constituted by a series of 10 keys 21 (FIGS. 1 and 4) for entering or setting the 10 digits of the decimal system. The keyboard is adapted to code the decimal numbers 25 in accordance with a biquinary code constituted by a quinary digit of weight 1 and a binary digit of weight 5. The keys 21 are adapted to act alternately on one or the other of two series of five code bars 22a-22e (FIG. 5) and 23a-23e, respectively, 30 to set selectively one of the bars, which represent the quinary part of the decimal digits entered.

The mechanism moreover comprises another two code bars 24 and 25 respectively disposed in correspondence with the code bars 23 and 22 and adapted likewise to be actuated alternately and selectively by the keys 21. The code bars 24 and 35 25 represent the binary part of the coded decimal digit.

The quinary digits that are set are read cyclically by a slider 31 (FIG. 1) provided with two projections or extensions 32 and 33 for reading the digits set in the code bars 22 or the code bars 23. These digits are carried to a transfer register 40 constituted by a slider 34 (FIGS. 10 and 11) which temporarily stores the digit entered. Similarly, the binary digits are read cyclically by a slider 36 (FIG. 3) provided with two projections 37 and 38 for reading the bar 24 or the bar 25. The result of this reading is carried to a transfer register constituted by a slider 39 (FIGS. 13 and 14). The slider 34 is provided with two storage devices 41 and 42 (FIGS. 10 and 11) adapted to store the same quinary digit and to be read alternately by two readers 43 and 44. In the same way, the slider 39 is provided with two devices 51 and 52 (FIGS. 13 and 14) both adapted to store the same binary digit and to be read alternately by two readers 53 and 54. The changeover between the reader 43 and the reader 44 and between the reader 53 and the reader 54 is controlled by the depression of a generic operating key of the calculating machine.

55 Finally, the data read by the readers 43 and 53 and by the readers 44 and 54 are respectively carried to two setting stores 56 and 58.

Keyboard

60 The numerical keyboard is constituted by the ten keys 21 (FIGS. 1 and 4) arranged on the front left-hand part of the machine with the keys corresponding to the digits from 1 to 9 aligned in three transverse rows and with the 0 key disposed on the left of the 1 key. Each of these keys 21 is supported by a 65 plane vertical plate 61 inclined with respect to the transverse and longitudinal planes of the keyboard. The plates 61 are all parallel to one another and are aligned in a single transverse row in correspondence with the central row of keys. Each plate 61 is guided in a fixed lower plate 66 and in a fixed upper plate 69. Each plate 61 is moreover normally caused to bear against the plate 69 under the action of a spring 70.

75 Each plate 61 is provided with two opposite projections 71 and 72 (FIGS. 1 and 4), the projection 71 being adapted to cooperate with a lug 73 of one of the code bars 22 and the projection 72 with a lug 74 of one of the code bars 23. More par-

ticularly, the projections 71 of the 0 key and of the 5 key are adapted to cooperate with the two lugs 73 of the code bar 22a and the projections 72 of the same keys are adapted to cooperate with the two lugs 74 of the code bar 23a; the projections 71 of the 1 and 6 keys are adapted to cooperate with the two lugs 73 of the bar 22b and the projections 72 of the same keys with the two lugs 74 of the bar 23b; the projections 71 of the 2 and 7 keys are adapted to cooperate with the two lugs 73 of the bar 22c and the projections 72 of the same keys with the two lugs 74 of the bar 23c; the projections 71 of the 3 and 8 keys are adapted to cooperate with the two lugs 73 of the bar 22d and the projections 72 of the same keys with the lugs 74 of the bar 23d; finally, the projections 71 of the 4 and 9 keys are adapted to cooperate with the two lugs 73 of the bar 22e and the projections 72 of the same keys with the lugs 74 of the bar 23e. The code bars 24 and 25, on the other hand, are provided with a series of five lugs 76 and 77, respectively, adapted to cooperate with projections 78 and 79, respectively, formed on the plates 61 of the keys corresponding to the numbers 0, 1, 2, 3 and 4.

The code bars 22, 23, 24 and 25 are all disposed transversely in the frame of the keyboard and are carried by two pairs of plates 81 and 82 (FIGS. 1 and 3) fixed to the two sides of the plates 66 and 69. Each of the bars 22a-22e is provided with two extensions 83a-83e and 84a-84e engaged in two slots 86a-86e and 87a-87e formed respectively in the plates 81 and in the plates 82. Each of the bars 23a-23e is provided with two extensions 88a-88e and 89a-89e engaged respectively in two slots 91a-91e and 92a-92e in the plates 81 and 82. Similarly, the bar 24 is provided with two extensions 93 and 94 engaged respectively in two slots 96 and 97 in the plates 81 and 82 and the bar 25 is provided with two extensions 98 and 99 engaged in two slots 101 and 102 in the plates 81 and 82. The slots 86, 87, 91, 92, 101 and 102 have substantially the shape of an eight, thus forming a guide for the transverse movements of the respective bars and a pivot for the rotation of the bars.

Each code bar 22 is moreover provided with a projection 111 (FIGS. 2 and 4) and each code bar 23 with a projection 112. Similarly, the code bar 24 is provided with a projection 113 and the code bar 25 with a projection 114. The projections 111 and the projection 114 are adapted to cooperate respectively with the right face and the left face of a universal bar 116 (FIG. 5) carried by a rocker 117 which can turn in two notch in the plates 66 and 69. The projections 112 and the projection 113 (FIG. 2), on the other hand, are adapted to cooperate respectively with the right face and the left face of another universal bar 119 (FIG. 5) carried by the rocker 117. The universal bar 116 of the rocker 117 is connected to a lever 120 (FIGS. 2 and 6) pivoted on a fixed spindle 121 and connected by a pin and slot to a lever 122 pivoted on a fixed pin 123. The lever 122, in turn, is connected by a pin and slot to a lever 126 pivoted on a fixed spindle 127 and normally bearing under the action of a spring 128 against a cam 129 on a main shaft 130 rotatable in the frame of the machine.

The code bars 22 and 23 (FIGS. 2 and 4) are moreover provided with projections 131 and 132 and with springs 133 and 134 which pull the code bars to the left so that the projection 131 or 132 bears against the plate 81, and the projection 111 or 112 bears against the universal bar 116 or 119 of the rocker 117. The springs 133 are moreover adapted to hold the respective code bars 22 turned anticlockwise (FIG. 5), while the springs 134 hold the code bars 23 turned clockwise. In each plate 81 and 82 there are formed two series of five rectangular slots 141, 142 which are aligned vertically and disposed respectively in correspondence with the paths of the individual projections 131 and 132 of the code bars 22 and 23 (FIG. 1).

Similarly, the code bars 24 and 25 are provided with projections 143 and 144, (FIG. 2) and with springs 146 and 147 adapted to pull the respective code bar to the right so that one of the projections 143 and 144 bears against the right side 82 of the keyboard, and the projection 113 or 114 bears against

the universal bar 119 or 116 of the rocker 117. The spring 146 is moreover adapted to hold the bar 24 (FIG. 5) turned clockwise and the spring 147 is adapted to hold the bar 25 turned anticlockwise. Finally, in each plate 82 there is formed a slot 148, 149, disposed respectively in correspondence with the paths of the projections 143 and 144 of the code bars 24 and 25.

In the position shown in FIGS. 1 and 2, the code bars 22 bear against the plate 81 with their respective projections 131 and are located with their lugs 73 in the path of the corresponding projections 71. Similarly, the code bar 24 is caused to bear against the plate 82 with its projection 143 and is located with the lugs 76 in the path of the corresponding projections 78. The code bars 23 and the code bar 25, on the other hand, have their projections 112 and 114 respectively bearing against the universal bars 119 and 116 of the rocker 117 and have the lugs 74 out of the path of the projections 72 and the lugs 77 out of the path of the projections 79.

Each code bar 22 is moreover provided with another projection 151 (FIG. 2). All these projections are adapted to cooperate with a frame 153 pivoted in the frame of the machine. The frame 153 is moreover engaged (FIG. 3) in a slot 157 of a slider 158 (FIG. 2) guided by means of a slot 159 on a pin 160 of the plate 66. In the same way, each code bar 23 is provided with another projection 161, all these projections being adapted to cooperate with a frame 163 pivoted in the frame of the machine and engaged in the slot 157 of the slider 158 (FIG. 2), which is connected to a lever 168 pivoted on a fixed spindle 169. Under the action of a spring 171, the lever 168 is normally caused to bear against a fixed pin 172. The lever is moreover arranged (FIG. 7) to cooperate with a pair of release teeth 174 (FIG. 13) of a clutch 176 which, are located diametrically opposite to each other with respect to the shaft 130. Therefore the clutch 176 when it is closed or engaged, connects a driving shaft 178 (FIG. 7) to the main shaft 130 and causes the main shaft 130 (FIG. 13) to perform a clockwise rotation of 180°; in a manner known per se.

Finally, each plate 61 (FIG. 1) is adapted to cooperate with a crosspiece of a bail 182 pivoted in two fixed slots 183. The bail 182 is provided with an arm 184 which operates a time switch of a type known per se and not shown in the drawings. The time switch is included in the circuit of the usual electric motor, which rotates the driving shaft 178.

45 Transfer registers

The slider 31 (FIGS. 1 and 10) is guided longitudinally by means of two slots 201 and 202 which engage two pins 203 and 204 (FIG. 10) on the plate 81. The two reading projections 32 and 33 (FIG. 1) of the slider 31 are alike and are each constituted by a step system having five steps located in correspondence with the paths of the projections 83a-83e and 88a-88e, respectively, of the bars 22 and 23.

The slider 31 is provided with a vertical slot 211 (FIG. 10) in which there is engaged a stud 212 of a rocking lever 213 pivoted on a pin 214. The pin 214 is carried by a lever 216 pivoted on the fixed spindle 127 and adapted to cooperate under the action of a spring 218 with a cam 219 on the main shaft 130.

60 The rocking lever 213 is normally held in the vertical inoperative position by a spring 218 attached to the lever 216 through the bearing of the slider 31 and the rocking lever itself against two fixed stops 233 and 234. The slider 31 is moreover pulled forward by a spring 236 over which the action of the spring 218 prevails. The slider 31 is furthermore connected by a pin and slot to a lever 243 pivoted on a fixed spindle 244 and provided with a stepped sector having five steps 247 adapted to cooperate selectively with a stud 248 on the rocking lever 213.

65 Finally, the slider 31 is provided with a pin 252 which can cooperate with a slot 253 in the slider 34, which is guided in its longitudinal movements through the medium of the slot 253 on the pin 252 and through the medium of a slot 254 (FIG. 11) on a fixed pin 255. The slider 34 is adapted to cooperate by means of its front end 256 (FIG. 10) with a stud 257 of a

rocking lever 258 pivoted on a fixed spindle 259 and connected by means of a link 261 to the stud 248 of the rocking lever 213. The slider 34 moreover cooperates with a spring positioning detent 264 adapted to hold it in five different positions.

The slider 34 is provided with two storage devices 41 and 42 (FIGS. 10 and 11), each of which is constituted by a symmetrical pair of stepped profiles 271, 272 and 273, 274, respectively, each of these profiles consisting of five steps.

The slider 36 (FIGS. 3, 13 and 14), in turn, is guided in its longitudinal movements by two slots 301 and 302 which engage two pins 303 and 304 on the plate 82 of the keyboard and is provided with two reading projections 37 and 38 (FIG. 3) which are alike and are respectively located in correspondence with the paths of the extensions 94 and 99 of the code bars 24 and 25.

The slider 36 is provided with a vertical slot 311 (FIG. 13) in which there is engaged a stud 312 of a rocking lever 313 pivoted on a pin 314. The pin 314 is carried by a lever 316 pivoted on the spindle 127 and adapted to cooperate under the action of a spring 318 with a cam 319 on the main shaft 130. The cam 319 is identical to the cam 219 and is in phase therewith. The rocking lever 313 is normally held in the vertical inoperative position by means of a spring 318 attached to the lever 316 through the bearing of the slider 36 and the rocking lever itself against two fixed stops 323 and 324. The slider 36 is pulled forward by a spring 326 and is connected by a pin and slot to a lever 333 which is pivoted on the spindle 244 and is provided with two steps 337, 338 adapted to cooperate selectively with a stud 339 of the rocking lever 313.

Finally, the slider 36 is provided with a pin 342 adapted to cooperate with a slot 343 in the slider 39, which is guided in its longitudinal movements by the slot 343 itself on the pin 343 and by a slot 344 (FIG. 14) on a fixed pin 345. The slider 39 is adapted to cooperate by means of its front end 346 (FIG. 13) with a stud 347 of a rocking lever 348 pivoted on the spindle 259 and connected by means of a link 351 to the stud 339 of the rocking lever 313. The slider 39 cooperates with a spring 354 adapted to hold it in two different positions. As already stated, hereinbefore, the slider 39 is provided with two storage devices 51 and 52 (FIGS. 13 and 14) each of which is constituted by a symmetrical pair of profiles 361, 362 and 363, 364, respectively.

Setting stores

The two stores 56 and 58 are alike. For simplicity, only the store 56 will be described, it being understood that the numerals relating to the store 58 will be distinguished by a prime. The store 56 comprises a reader constituted by a rocking lever 411 (FIGS. 6 and 10) guided by a slot 412 on a fixed pin 413 and normally bearing under the action of a spring 414 against two fixed stops 416.

The rocking lever 411 is provided with two bent lugs 426 and 427 adapted to cooperate with the stepped profiles 271 and 272, respectively, of the storage device 41. The two lugs 426 and 427 are at a distance apart such that they are able to read two complementary values on the two stepped profiles. The rocking lever 411 is moreover connected by a pin and slot to a crank 432 fixed to a bar 433 which can turn in two fixed plates 428 FIG. 6 of the store through the medium of two pivotlike ends 434 and 435. The intermediate portion of the bar 433 is of rectangular section with the edges rounded and with the pivots 434 and 435 disposed in the lower part of this section. A slot 436 of a setting lever 438 is slideable on the bar 433.

The rocking lever 411 is further connected by a pin and slot to a crank 443 fixed to a bar 444 which can turn by means of two pivotlike ends 446 and 447 in the frame of the store. The intermediate portion of the bar 444 is also of substantially rectangular section with the pivots 446 and 447 disposed in the lower portion of this section. A setting lever 451 is slideable on the bar 444 by means of a slot 448. Each of the levers 438 and 451 is engaged in a slot 458 in a horizontal plate 460 forming a part of a carriage 461 guided on a fixed

transverse bar 463 (FIG. 10). The carriage 461 (FIG. 6) engages with a pinion 462 which is rotatable step by step by means of a step-by-step advancing device of any known type. The two advancing devices are actuated alternately by a cam on the main shaft 130, the cam not being shown in the drawings, and the changeover is controlled by the operating keys in known manner. The two levers 438 and 451 are disposed in the same longitudinal plane and are adapted to cooperate in succession with lugs 468 of a series of storage bars 469 each of which is adapted to be held in five different positions by a leaf-spring positioning element 471 and is therefore adapted to store a quinary digit. In FIG. 10, the storage bars 469 are storing the digit zero.

The store 56 comprises a second reader constituted by a rocking lever 491 which is adapted to read cyclically the digits set in the slider 39 and stored temporarily by the device 51. The rocking lever 491 is guided by a slot 492 on a fixed pin 493 and normally bears under the action of a spring 494 against two fixed stops 495.

The rocking lever 491 is provided with two bent lugs 496 and 497 adapted to cooperate with the two-stepped profiles 361 and 362 of the storage device 51. The two bent lugs 496 and 497 are at a distance apart such that they are able to read two complementary values on the profiles. The rocking lever 491 is moreover connected by a pin and slot to a crank 502 fixed to a bar 503 which can turn through the medium of two pivotlike ends 504 and 505 in the frame of the machine. The intermediate portion of the bar 503 is of substantially rectangular section with the pivots 504 and 505 disposed in the lower part of this section. Slidable on the bar 503 by means of a slot 506 is a setting lever 508. The rocking lever 491 is connected by a pin and slot to a second crank 513 fixed to a bar 514 which can turn by means of two pivotlike ends 516 and 517 in the frame of the machine. The intermediate portion of the bar 514 is also of rectangular section, with the pivots 516 and 517 disposed in the lower part of this section. Slidable transversely on the bar 514 by means of a slot 518 is a lever 521. The two levers 508 and 521 are engaged in a slot 528 in the plate 460 of the carriage 461. The two levers 508 and 521 are disposed in the same longitudinal plane and are adapted to cooperate in succession, under the control of the step-by-step advance, with lugs 538 of a series of storage bars 539, each of which is adapted to be held in two different positions by a spring positioning element 541 and is therefore adapted to store a binary digit.

The changeover between the two stores 56 and 58 is controlled by the operating keys which act, via a kinematic chain of any known type, on two bars 601 and 602 which are moved longitudinally alternately into two different positions in which they are then held in any known manner. The two bars 601 and 602 provide respectively for the changeover or exchange between the stores 56 and 58. The bar 601 (FIGS. 6, 8 and 10) carries two cranks 606 and 606' alternately adapted to cooperate with two projections 607 and 607' of the rocking levers 411 and 411'. In the drawings, the crank 606 is located in correspondence with the projection 607, while the crank 606' is out of engagement with the projection 607'. Similarly, the bar 602 (FIGS. 7, 8 AND 13) carries two cranks 608 and 608' alternately adapted to cooperate with two projections 609 and 609' of the rocking levers 491 and 491'. In the drawings, the crank 608 is in correspondence with the projection 609, while the crank 608' is out of engagement with the projection 609'. The bar 601 (FIGS. 6 and 10) is provided with a pin 611 engaged in a horizontal slot 612 in a slider 613 (FIG. 10) guided by means of two slots 614 on two fixed pins 616. The slider 613 is connected by a pin and slot to a lever 617 pivoted on the spindle 127 and normally bearing under the action of a spring 619 against a cam 620 on the main shaft 130. Similarly, the bar 602 (FIG. 13) is provided with a pin 621 engaged in a slot 622 in a slider 623 guided by means of two slots 624 on two fixed pins 626. The slider 623 is moreover connected by a pin and slot to a lever 627 pivoted

on the spindle 127 and normally bearing under the action of a

spring 629 against a cam 630 on the main shaft 130. The cam 630 is identical to the cam 620 and is in phase therewith.

Operation

On the depression of a numerical key 21 (FIG. 5), the corresponding plate 61 acts first of all on the crosspiece of the bail 182, thus causing the closing of the switch controlling the starting of the motor, which sets the driving shaft 178 (FIG. 7) in rotation. Continuing its downward movement, the plate 61 (FIG. 1) encounters, by means of the projection 71 or the projection 72, the lugs 73 or 74 of the code bar 22 or 23 corresponding to the key that is depressed. In addition, if the key corresponds to one of the numbers from 0 to 4, the plate 61 encounters one of the lugs 76 and 77 of the bar 24 or 25 by means of the projection 78 or the projection 79.

Let us be assumed, for example that the keyboard is in the state shown in FIG. 2 and that the 0 key is depressed. The projection 71 and the projection 78 of the plate 61 of the 0 key act on a lug 73 and a lug 76, respectively, of the code bars 22a and 24. The code bar 22a (FIG. 1) is turned clockwise until its projection 131 enters the corresponding slot 141 in the left side 81. The spring 133 (FIG. 2) associated with this code bar causes the bar to shift to the left, thus bringing the extension 83a into the path of the step system 32 of the slider 31. The code bar 24 (FIG. 3), on the other hand, is turned anticlockwise until the projection 143 enters the slot 148 in the right side 82. The spring 146 (FIG. 2) causes this bar to translate to the right, so that the extension 94 is brought into the path of the projection 37 of the slider 36. The shifting of the code bar 22a to the left causes, via the corresponding projection 151, the anticlockwise turning of the frame 153 and, therefore, via the slider 158, the anticlockwise turning of the lever 168, which causes the closing or engagement of the clutch 176 (FIG. 7), thus setting the main shaft 130 in rotation for a rotation cycle of 180°.

The operations of reading and setting the data will be described with reference to the diagram illustrating the cycle of the main shaft 130 which is given in FIG. 16. In the first 60° of rotation of the main shaft, the cam 219 (FIG. 10) causes the lever 216 to turn clockwise. The pin 214 is shifted forward and thus permits the slider 31 to shift forward under the action of the spring 236. The rocking lever 213 therefore begins a clockwise rotation which is interrupted when the step system 32 (FIG. 1) encounters the extension 83 of the code bar 22 which has been actuated by the depressed key. In the case under examination, in which the 0 key has been depressed, the slider 31 performs only the stroke corresponding to the making up of the gap which there is at rest between the extension 83a of the bar 22a and the corresponding step of the projection 32.

The pin 214 (FIG. 10) continues its forward movement and the rocking lever now turns anticlockwise about the stud 212 as far as the position shown in chain-dotted lines in FIG. 10, in which the stud 248 bears against the first of the steps 247. During this movement, the rocking lever 213 turns about the pin 214 by a number of steps which is complementary to the value of the quinary digit entered. The rotation of the rocking lever 213 causes the rotation of the rocking lever 258 for the same number of steps via the link 261 and the last-mentioned rocking lever cooperates with the front end 256 of the slider 34. The forward movement of the slider 31 by a number of steps equal to the value of the quinary digit entered moreover brings the pin 252 against the end of the slot 253 in the slider 34, which is thus set positively in the position corresponding to the quinary digit of the decimal number entered. The two pairs of stepped profiles 271, 272 and 273, 274 (FIGS. 10 and 11) are thus both positioned in accordance with the quinary digit of the decimal number entered.

At the same time and in similar manner, the binary digit is set in the slider 39 (FIG. 13). The cam 319 causes the lever 316 to turn clockwise and thus causes the pin 314 to shift forward. In the case under examination, after a first turning movement clockwise to make up the gap existing at rest between the projection 37 of the slider 36 and the extension

94 of the code bar 24, the rocking lever 313 turns anticlockwise until the stud 339 bears against the step 337 of the lever 333. If a key corresponding to a number from five to nine is depressed, the slider 36 continues its forward movement until the pin 342 reaches the end of its travel in the slot 343. Consequently, the rocking lever 313 now continues the clockwise turning movement and the final position is determined by the bearing of the stud 339 against the step 338 of the lever 333.

Returning to the case under examination, in which decimal number 0 is being entered, the turning of the rocking lever 313 causes, via the link 351, the turning anticlockwise of the rocking lever 348, which bears through the medium of the stud 347 against the front end 346 of the slider 39. The pin

342 of the slider 36 bears similarly against the end of the slot 343 in the slider 39, which is thus positioned positively. The two pairs of profiles 361, 362 and 363, 364 (FIGS. 13 and 14) are thus both positioned in such manner as to store the binary digit of the decimal number entered.

In the arc of rotation between 60° and 120°, the cams 219 and 319 (FIGS. 10 and 13) bring back to rest the respective rocking levers 213 and 313 and, therefore, also the sliders 31 and 36 and the rocking levers 258 and 348. The two sliders 34 and 39, on the other hand, remain in the position into which they have been brought and thus store through the medium of the profiles 271, 272; 273, 274 and 361, 362; 363, 364, respectively, the quinary digit and the binary digit of the decimal number entered. In the arc of rotation between 120° and 180°, the two cams 219 and 319 have a portion of circular profile, so that the two systems controlled by them are held in the rest position.

For the first 60° of rotation of the main shaft 130, the cams 620 and 630 have a circular profile portion. The kinematic chains controlled by them therefore remain initially in the rest position. During this period, under the control of the shaft 130, the advancing device causes the pinion 462 to rotate by one step and the pinion causes the carriage 461 to advance by one step, while the other advancing device is disengaged and the carriage 461' remains in the rest position. The setting levers 438 and 451 (FIG. 10) are thus brought into correspondence with the first storage bar 469 for the quinary digit and the setting levers 508 and 521 (FIG. 13) are brought into correspondence with the first storage bar for the binary digit.

In the arc between 60° and 120°, the cams 620 and 630 cause the respective levers 617 and 627 to turn anticlockwise. The lever 617 carries the slider 613 downwards and this slider acts by means of the slot 612 on the pin 611 and causes the bar 601 to rotate in such manner that the crank 606 carries the rocking lever 411 upwards, while the crank 606' is raised idly, (compare FIGS. 6 and 8). The two lugs 426 and 427 (FIG. 10) of the rocking lever 411 bear on the two stepped profiles 271 and 272, respectively, and cause the cranks 432 and 443 to turn anticlockwise and clockwise, respectively, and, therefore, the two setting levers 438 and 451 to turn by a number of steps which are complementary to one another. In the case of the setting of the digit 0, the lever 438 turns by a small amount corresponding to the making-up of the gap existing between it and the first step of the stepped profile 271, while the lug 427 reads the last step and therefore causes the lever 451 to turn by four steps. The two levers 438 and 451 thus converge on the lug 468 of the first of the storage bars 469 and position this bar positively from the position previously occupied to the desired position, storing in this way the quinary digit of the decimal order entered.

Simultaneously, the lever 627 (FIG. 13) brings the slider 623 downwards and this slider acts by means of the slot 622 on the pin 621 and causes the bar 602 to rotate in such manner as to carry the cranks 608 and 608' upwards. The crank 608 carries the rocking lever 491 upwards, while the crank 608' is raised idly. The two lugs 496 and 497 of the rocking lever 491 bear on the two profiles 361 and 362, respectively, causing the two cranks 502 and 513 to turn anticlockwise and clockwise, respectively (FIG. 13), and, therefore, the two setting levers

508 and 521 to turn by a number of steps which are complementary to one another. In the case under examination concerning the setting of the 0, the lever 508 turns only by the amount corresponding to the making-up of the gap existing between it and the first step of the profile 361, while the lever 521 turns for the maximum stroke. The two levers 508 and 521 thus position the first of the storage bars 539 positively, storing in this way the binary digit of the coded decimal digit.

In the arc of rotation of the main shaft 130 between 120° and 180°, the cams 620 and 630 bring the two reading rocking levers 411 and 491 back to rest. It is therefore clear that the pairs of stepped profiles 271 and 272, 273 and 274, 361 and 362, 363 and 364 are adapted to be shifted variably according to the position that the storage bars are to reach and are adapted to be read simultaneously by the respective rocking levers 411, 411', 491 and 491', the pairs of levers 438 and 451, 438' and 451', 508 and 521, 508' and 521' being movable one towards the other under the control of said rocking levers and being adapted to engage the storage bars to bring them positively from any previously occupied position to the new position to be reached.

For the first 90° of rotation of the main shaft 130, the cam 129 has a circular profile portion, so that the kinematic chain controlled by it remains in the initial position of rest. After 90°, the cam 129 causes the lever 126 (FIG. 10) to turn clockwise and, therefore, the lever 122 (FIG. 6) to turn clockwise. The lever 120 (FIG. 2) turns anticlockwise and causes the rocker 117 to turn clockwise. The universal bar 119 permits the code bars 23 to shift to the left until the projections 132 bear against the side 81, while the universal bar 116 of the rocker 117 permits the code bar 25 to shift to the right until the projection 144 bears against the right side 82. The lugs 74 of the code bars 23 and the lugs 76 of the code bar 25 are now respectively located in the paths of the projection 72 and the projections 79 of the plates 61 of the relevant keys 21. It is therefore possible to set a new number before the end of the 180° cycle of the shaft 130 without this number being lost.

The recovery of the reading sliders 31 and 36 is not yet completed, but the fact that the extension 88 (FIG. 2) of the bar 23 which has been set bears against the projection 33 of the slider 31 and the fact that the extension 99 of the bar 25 (if this bar has been set) bears against the projection 38 of the slider 36 does not create drawbacks of any kind, since the lugs 74 and 77 have already been brought below the plates 61.

As it continues to turn, the universal bar 116 engages against the projection 111 of the bar 22 that has been set, bringing it to the right and releasing the relevant projection 131 from the slot 141. Similarly, if the bar 24 has been set, it is brought to the left, thus releasing the projection 143 from the slot 148 (FIG. 3) in the plate 82. The lugs 73 of the code bars 22 and the lugs 76 of the code bar 24 are respectively brought out of the paths of the projections 71 and the projections 78, thus effecting the release of these bars from the key which is possibly kept depressed. The spring 133 (FIG. 2) of the bar 22 which is set can therefore cause this bar to turn anticlockwise (FIG. 1), thus bringing the projection 131 out of the path of the slot 141. Similarly, the spring 146 (FIG. 2) causes the bar 24 to turn clockwise (FIG. 1) and thus brings the projection 143 out of the path of the slot 148.

The clutch 176 is now reopened and the main shaft stops. A new setting operation effected from this moment on takes place in identical manner to that described, with the sole variation of changeover or exchange between the code bars 22 and 24 and the bars 23 and 25, so that the setting of the various decimal orders in the store takes place alternately by means of the bars 22 and 24 and the bars 23 and 25, respectively.

At the end of the setting of a series of numbers constituting an operand, the depression of a function key, for example an addition key not shown in the drawings, causes the shifting of the two bars 601 and 602 (FIGS. 6, 7 and 8) to the rear. The cranks 606' and 608' are thus brought into correspondence

with the projection 607' and the projection 609', respectively, while the cranks 606 and 608 are brought out of engagement with the respective projections 607 and 609, as a result of which, during the addition of the number set in the store 56, another number can be set in the store 58.

In the second embodiment of the invention, shown in FIGS. 17 to 21, the bars 24 and 25 are replaced by two code bars 702 and 703 disposed in correspondence with the code bars 22 and 23, respectively, and also adapted to be actuated alternately and selectively by the keys 21. The code bars 702 and 703 are provided with a series of five lugs 704 and 705 (FIG. 18), respectively, adapted to cooperate with the projection 79 and 78, respectively, formed on the plates 61 of the keys corresponding to the decimal numbers 0, 1, 2, 3 and 4. The slots 86a-86e, 91a-91e and 87a-87e, 92a-92e are now formed in two pairs of plates 706 and 707, respectively. The code bar 702 is provided with two extensions 711 and 712 engaged in two slots 713 and 714, respectively, in the plates 706 and 707 and, finally, the code bar 703 is provided with two extensions 716 and 717 engaged in two slots 718 and 719 in the plates 706 and 707. The slots 713, 714, 718 and 719 are also substantially in the shape of an eight. The extension 712 (FIG. 18) is provided at the end with a lug 715 and the extension 717 with a lug 720. The two lugs 715 and 720 are now read by the reading slider 36.

The code bar 702 is provided with a projection 721 and the code bar 703 with a projection 722. The projection 111 and 721 now cooperate with a universal bar 726 and the projections 112 and 722 with a universal bar 727. The two universal bars 726 and 727 are pivoted on a fixed spindle 728 and are adapted to cooperate with two lugs 738 and 739, respectively, (FIGS. 17 and 19) of a plate 741. The plate 741 is guided in two slots 742 of a slider 744 so as to be movable longitudinally. The slider 744 is guided via two slots 745 on two fixed pins 743 and 746 and is normally pulled to the left by a spring 747. Through a kinematic chain known per se and not visible in the drawings, the slider 744 is controlled by a cam on the main shaft 130 (FIG. 10) having an actuation diagram given in FIG. 21, in which it is indicated by the number 750.

The plate 741 is provided with a slot 761 in which there is engaged a pin 762 of a lever 763 in the form of a cross and pivoted on the pin 746. The lever 763 is provided with a pin 767 engaged in a slot 768 in a slider 769. The slider 769 guided on two fixed pins 772 by means of two slots 771 and is held in two different positions by a spring-biased positioning detent 770. Moreover, the slider 769 is provided with two lugs 773 and 774 adapted to be engaged by two arms 776 and 777, respectively, of a rocking lever 778 pivoted on a pin 779 of the slider 744.

The rocking lever 778 is provided with a third arm 781 having a stud 782 engaged in a slot 783 in a slider 784. The slider 784, in turn, is provided with two slots 786 engaging two studs 787 on the slider 744. Finally, the slider 784 is provided with two pairs of shoulders 788 789 adapted to cooperate with two lugs 791 and 792, respectively, of lever 763.

The two universal bars 726 and 727 are moreover engaged respectively in a slot or notch 801 of a bar 802 and a slot or notch 803 of a bar 804. The two bars 802 and 804 are guided in the frame of the keyboard and are pulled to the left by springs 806 and 807. Moreover, the two bars 802 and 804 are provided with two lugs 808 and 809 adapted to bear against the pair of plates 706.

Finally, the bar 802 is provided with a projection 811 adapted to be engaged by a lug 812 (FIGS. 19 and 20) of a lever 813. The lever 813 can turn on a fixed pin 814 and is pulled anticlockwise by a spring 816. This lever is moreover provided with a projection 817 engaged in a notch 818 in a slider 819 guided in the frame of the keyboard. The slider 819 is provided with five studs 822a-822e adapted to cooperate with the code bars 23a-23e, respectively.

Similarly, the bar 804 is provided with a projection 831 adapted to be engaged by a lug 832 of a lever 833 which can turn on a fixed pin 834 and is pulled clockwise by a spring 836.

The lever 833 is provided with a projection 837 engaged in a notch 838 in a slider 839 guided in the frame of the keyboard. The slider 839 is provided with five studs 843a-843e adapted to cooperate with the code bars 22a-22e, respectively.

Finally, the bars 702 and 703 (FIG. 18) are provided with projections 851 and 853, respectively, and are pulled to the left by springs 852, 854. The springs 852 and 854 hold the respective code bars 702 and 703 turned anticlockwise and clockwise, respectively.

The rectangular slots 141 and 142 are now disposed in the plates 706, in which, finally, there is formed another slot 861, 862, respectively, disposed in correspondence with the path of the projection 851 and the projection 853, respectively, of the code bars 702 and 703.

On the depression of one of the numerical keys 21 (FIG. 17), the relevant plate 61, moving downward, acts on the switch of the motor circuit substantially as described in the case of the preceding embodiment. Continuing its downward movement, the plate 61 encounters, by means of the projection 71 or the projection 72, the lug 73 or 74, respectively, (FIG. 18) of the code bar 22 or 23 corresponding to the key depressed. Moreover, if the key corresponds to one of the numbers from 0 to 4, the plate 61 encounters, by means of the projection 79 or the projection 78, one of the lugs 704 or 705 of the bar 702 or 703. In the situation shown in the drawings, the bars 22 and the bar 702 are concerned at first.

The code bar 22 concerned (FIG. 1) is turned clockwise until its projection 131 is brought in front of the corresponding slot 141 in the plate 706. The spring 133 (FIG. 18) associated with this code bar 22 causes the bar to shift to the left, bringing the projection 131 into the slot 141 and, therefore, the relevant extension 83 into the path of the reading slider 31. If the key depressed corresponds to one of the decimal numbers from 0 to 4, the bar 702 (FIG. 17) is also turned clockwise until its projection 851 enters the slot 861 in the plate 706, thus bringing the lug 715 (FIG. 18) into a position such as to involve the reading slider 36.

The code bar 22 concerned shifts the slider 839 (FIG. 20) upwards via the corresponding stud 843 and, via the projection 837, the slider causes the lever 833 to turn clockwise. This consequently removes the lug 832 from the path of the projection 831 of the bar 804. The spring 807 (FIG. 19) now shifts the bar 804 to the left and causes the universal bar 727 (FIG. 18) to turn clockwise, thus permitting the code bars 23 and 703 to shift to the left until they bear against the plate 706 by means of their respective projection 132 and 853. The bars 23 and 703 are thus prearranged for setting substantially simultaneously with the actual setting of the code bars 22 and 702.

The shifting of the set code bar 22 to the left causes the closing of a clutch which sets the main shaft 130 in rotation and effects the reading of the digit represented by the set code bars 22 and 702 and the transfer of this digit to the setting store substantially as described in the case of the preceding embodiment.

The phase of reading the digit having been completed, that is when the main shaft has rotated through about 60°, the cam 750 (FIG. 21) causes the slider 744 (FIG. 19) to shift to the right, overcoming the action of the spring 747. The slider 744 brings to the right the plate 741, the lug 738 of which engages the universal bar 726, causing it to turn clockwise. The universal bar 726, in turn, engages the projection 111 (FIG. 18) of the set code bar 22 and the projection 721 of the code bar 702, if this has been set. These two code bars are pushed to the right until their projections 131 and 851, respectively, are disengaged from the slots 141 and 861 (FIGS. 17 and 18). As soon as the two code bars 22 and 702 concerned are released, they are turned anticlockwise by the respective springs 133 and 852 in such manner as to bring the respective projections 131 and 851 out of the path of the slots 141 and 861.

The universal bar 726 also pushes the bar 802 (FIG. 19) to the right, thus removing the projection 811 from the path of the lug 812 of the lever 813 (FIG. 20), which is now free to

turn anticlockwise. The lever 813 positions itself with the lug 812 in the path of the bar 802 and carries down the slider 819 with the studs 822a-822e in contact with the respective code bars 23a-23e.

5 Via the pin 779, the slider 744 (FIG. 19) also brings the rocking lever 778 to the right. The arm 777 of this rocking lever encounters the lug 774 of the slider 769, so that the rocking lever 778 turns clockwise and shifts the slider 784 to the rear via the arm 781. The slider 784 brings the upper shoulder of the pair of shoulders 789 into correspondence with the lug 792 of the cross-shaped lever 763 and the lower shoulder of the pair of shoulders 788 into correspondence with the lug 791 of the cross-shaped lever 763.

15 After the main shaft has rotated through about 120°, the cam 750 (FIG. 21) permits the slider 744 (FIG. 19) to return to the left. The two pairs of shoulders 788 and 789 engage the lugs 791 and 792, respectively, of the lever 763, which is turned clockwise.

20 Via the pin 767, the lever 763 shifts the slider 769 formed and the slider brings its lug 773 into the path of the arm 776 of the rocking lever 778. The slider 769 is then held by the spring-biased positioning element 770 in the position reached. 25 Moreover, via the pin 762, the lever 763 shifts the plate 741 to the rear and this plate brings its lug 739 into correspondence with the universal bar 727 and its lug 738 out of the path of the universal bar 726. Therefore, by now depressing a key 21, the corresponding plate 61 sets one of the bars 23 and, if necessary, the bar 703, in a manner similar to that hereinbefore seen in the case of the bars 22 and 702.

30 It is therefore clear that the two encoding mechanisms 22, 702 and 23, 703 are brought back to rest by two universal bars 726 and 727 which are independent and adapted to be actuated alternately and that the means 813, 833 controlled by the two mechanisms prearrange either of the two mechanisms for setting simultaneously with the setting of the other mechanism.

35 40 Various modifications, with the addition or elimination of parts, may be made without departing from the scope of the invention. For example, the pairs of cranks 606a, 606b and 608a, 608b (FIGS. 10, 11, 13 and 14) may be mounted slidably on the respective bars 601 and 602, so that each pair 45 can be controlled individually by the various function keys, in such manner as to introduce the data selectively into one store or the other or into both simultaneously. Moreover, the cams 129, 219 and 319, 620 and 630 are shown in accordance with one possible plan of operation, but the cam 129, for example, 50 could have an actuation diagram operative in the part of the cycle between 60° and 120°.

I claim:

1. A mechanism for entering and storing up to a predetermined number of information characters comprising:
a frame;
a store including a settable member for each of said predetermined number of characters;
means for receiving a character from a source;
transfer register means comprising a transfer member movably mounted on said frame and cooperating with said receiving means to be differentially moved according to the value of the character entered into said receiving means for positionally indicating said value;
a stepped extension fixedly mounted on said transfer member and movable therewith, said stepped extension having a plurality of shoulders of varying depth according to the various positions of said transfer member;
reading means including a sensing element movable for engagement with one of the shoulders of said extension for sensing the position of said transfer member; and
positioning means movable under the control of said sensing element for bringing a selected one of said settable members to a position corresponding to the position of the sensed transfer member.

2. A mechanism as recited in claim 1, wherein said transfer member is formed of a slider movable in a first direction in accordance with the value of the character entered by said receiving means, said sensing member being movable in a second direction substantially perpendicular to said first direction for sensing the shoulders of said slider.

3. A mechanism as recited in claim 2, wherein each one of said settable members includes a projection, and wherein said positioning means comprise two positioning members movable in opposite directions under the control of said sensing element for positively engaging two opposite edges of said projection of the selected one of said settable members to bring this latter member from any previous position to the position corresponding to the value of the character entered into said receiving means and indicated by the position of said slider.

4. A mechanism according to claim 3 wherein said transfer register means further include a second extension mounted on said slider and movable therewith and having a profile of complementary configuration with respect to said profile of the other extension, and wherein said reading means further includes:

a second sensing element for sensing said second extension; and
a rocking lever carrying said sensing elements on opposite ends thereof, said sensing elements being spaced for engagement with complementary ones of said shoulders of said extensions, said sensing elements being associated with, and individually connected with said two positioning members, said rocking lever being operable for causing said sensing elements to simultaneously sense said extensions.

5. A mechanism as recited in claim 4 further comprising two bars coupling the rocking lever to said positioning members, said members being mounted on said bars for longitudinal movement for being brought into correspondence with the successive settable members, said bars being rotatable by complementary amounts under the control of said rocking lever for actuating said positioning members.

6. A mechanism as recited in claim 2, wherein said characters are formed of decimal figures encoded according to a biquinary code, and wherein said settable member is movable into one of five different positions for storing the quinary portion of the biquinary figure under the control of said positioning means, further comprising:

a second settable member included in said store for each of said figures, and movable into one of two different positions for storing the binary portion of said biquinary figure; a second slider movable in accordance with the figure entered by said receiving means, a second transfer member included in said transfer register means for positionally indicating the figure entered into said receiving means, second reading means for sensing the position of said second transfer member; and second positioning means movable under the control of said second reading means for bringing a selected one of said second settable members to a position corresponding to the figure entered into said receiving means and sensed by said second reading means.

7. A mechanism as recited in claim 6, further comprising a carriage transversely movable step by step on said frame with respect to said settable members, said first and second positioning means being carried by said carriage for simultaneously setting the successive pairs of said settable members.

8. A mechanism entering and storing up to a predetermined number of information characters comprising:

a set of keys for entering an information character; an encoding device for encoding a character entered by one of said keys, said encoding device comprising five code bars settable individually and selectively on the depression of one of said keys for indicating the quinary portion of a biquinary character and a further code bar settable

selectively in combination with said five code bars for indicating the binary portion of said biquinary character; transfer register means including means for positionally indicating the value of the character encoded by said encoding device;

a first reading slider having a stepped projection, said first reading slider being movable into one of five positions under the control of said five code bars, and

a second reading slider having a projection and being movable into one of two positions under the control of said further code bar, said sliders cooperating with said transfer register means for bringing said indicating means from a previously occupied position to the position corresponding to the value of the character encoded on said encoding device.

9. A mechanism as recited in claim 8, wherein said positioning means further comprise for each of said reading sliders means for biasing the corresponding reading slider in one direction, a pin shiftable in said direction by a predetermined stroke, a rocking lever having a clamped position and pivotally mounted intermediate its ends on said pin, one end of said rocking lever being coupled to said reading slider for holding said reading slider against the action of said biasing means while said rocking lever is in said clamped position, said pin operating to hold said lever in said clamped position while said pin is at one end of its stroke, the movement of said pin through its stroke operating to release said rocking lever for allowing said slider to move under the control of said biasing means by an amount determined by the associated code bars for moving the other end of said rocking lever into a position corresponding to the value of character coded on said associated code bars.

10. A mechanism as recited in claim 9, wherein said positioning means further comprise for each of said reading sliders a pivotally mounted bellcrank having one arm coupled to said reading slider, the other arm including a face having a stepped profile, the movement of said reading slider under the control of said biasing means acting to rotate said bellcrank for bringing one of the steps of said profile into engagement with the other end of said rocking lever.

11. A mechanism as recited in claim 10, wherein said positioning means further comprise for each of said reading sliders a second rocking lever coupled to said other end of said rocking lever and rotatable under the control thereof, a pair of positioning members, one of said positioning members being fixed to the reading slider, the other positioning member being fixed to said second rocking lever, the rotation of said second rocking lever and the movement of said reading slider acting to move said pair of positioning members in opposite directions for positively bringing said indicating means to the position corresponding to the character encoded on said encoding device.

12. A mechanism for entering and storing up to a predetermined number of information characters comprising:
a set of keys for entering an information character;
a pair of encoding devices for encoding characters entered by said keys;
changeover means for rendering alternatively operative said encoding devices, and
actuating means operable on the depression of each of said keys for operating said changeover means.

13. A mechanism as recited in claim 12, wherein each of said encoding devices comprises a series of quinary code bars and a binary code bar, said changeover means including universal bar alternately settable in two different positions by said actuation means for alternatively enabling one of said encoding devices and restoring the other.

14. A mechanism as recited in claim 12, wherein said changeover means comprise two universal bars associated each one with said encoding devices and alternatively settable under the control of said actuating means for alternatively restoring said encoding devices and release means controlled by said actuating means for resetting either universal bar sub-

15

stantially simultaneously with the setting of the encoding device associated with the other universal bar.

15. A mechanism as recited in claim 14, wherein said actuating means further comprise an element for alternatively setting said universal bars and means operable after said element sets one universal bar for shifting said element for enabling it to set the other universal bar.

16. A mechanism as recited in claim 15, wherein said means for shifting said element of the actuating means comprise a pivotally mounted cross-shaped lever positionable alternately

16

in one of two positions, said actuating means further comprising a member alternatively shiftable into two positions for cooperation with the arms of said cross-shaped lever for rotating it positively from one of its positions to the other.

5 17. A mechanism as recited in claim 16, further comprising a two-position operating slider controlled by said cross-shaped lever and a rocking lever for shifting said member under the control of said two-position operating slider.

10 18. A mechanism as recited in claim 17, further comprising a two-position operating slider controlled by said cross-shaped lever and a rocking lever for shifting said member under the control of said two-position operating slider.

15 19. A mechanism as recited in claim 18, further comprising a two-position operating slider controlled by said cross-shaped lever and a rocking lever for shifting said member under the control of said two-position operating slider.

20 20. A mechanism as recited in claim 19, further comprising a two-position operating slider controlled by said cross-shaped lever and a rocking lever for shifting said member under the control of said two-position operating slider.

25 21. A mechanism as recited in claim 20, further comprising a two-position operating slider controlled by said cross-shaped lever and a rocking lever for shifting said member under the control of said two-position operating slider.

30 22. A mechanism as recited in claim 21, further comprising a two-position operating slider controlled by said cross-shaped lever and a rocking lever for shifting said member under the control of said two-position operating slider.

35 23. A mechanism as recited in claim 22, further comprising a two-position operating slider controlled by said cross-shaped lever and a rocking lever for shifting said member under the control of said two-position operating slider.

40 24. A mechanism as recited in claim 23, further comprising a two-position operating slider controlled by said cross-shaped lever and a rocking lever for shifting said member under the control of said two-position operating slider.

45 25. A mechanism as recited in claim 24, further comprising a two-position operating slider controlled by said cross-shaped lever and a rocking lever for shifting said member under the control of said two-position operating slider.

50 26. A mechanism as recited in claim 25, further comprising a two-position operating slider controlled by said cross-shaped lever and a rocking lever for shifting said member under the control of said two-position operating slider.

55 27. A mechanism as recited in claim 26, further comprising a two-position operating slider controlled by said cross-shaped lever and a rocking lever for shifting said member under the control of said two-position operating slider.

60 28. A mechanism as recited in claim 27, further comprising a two-position operating slider controlled by said cross-shaped lever and a rocking lever for shifting said member under the control of said two-position operating slider.

65 29. A mechanism as recited in claim 28, further comprising a two-position operating slider controlled by said cross-shaped lever and a rocking lever for shifting said member under the control of said two-position operating slider.

70 30. A mechanism as recited in claim 29, further comprising a two-position operating slider controlled by said cross-shaped lever and a rocking lever for shifting said member under the control of said two-position operating slider.

75 31. A mechanism as recited in claim 30, further comprising a two-position operating slider controlled by said cross-shaped lever and a rocking lever for shifting said member under the control of said two-position operating slider.

UNITED STATES PATENT OFFICE
CERTIFICATE OF CORRECTION

Patent No. 3,598,305 Dated August 10, 1971

Inventor(s) ETTORE ABBIATI

It is certified that error appears in the above-identified patent and that said Letters Patent are hereby corrected as shown below:

Priority is also claimed on the basis of Italian Patent
Application No. 50822-A/69 dated March 3, 1969.

Signed and sealed this 18th day of April 1972.
